UNITED STATES PATENT OFFICE.

FIELDEN B. ASHENFELTER, OF TOLEDO, OHIO.

LOCK MEANS.

Application filed October 13, 1924. Serial No. 743,228.

To all whom it may concern:

Be it known that I, FIELDEN B. ASHENFELTER, a citizen of the United States, and a resident of Toledo, in the county of Lucas and State of Ohio, have invented a new and useful Lock Means, which invention is fully described in the following specification.

This invention relates to a lock, particularly intended for use in connection with the control or regulating means for windows of the character used in closed vehicles; and has for its object the provision of a simple and efficient lock of this character which will be automatically released and permit a free raising or lowering of the associated window member when power for such purpose is applied to the operating crank of the window regulating means, and is adapted to automatically lock and prevent movement of the regulating means when power is applied to the window member or the window member coating side of the regulating means.

The invention is fully described in the following specification and, while in its broader aspects, it is capable of embodiment in numerous forms, a preferred embodiment thereof is illustrated in the accompanying drawings, in which—

Figure 1 is a side elevation of the regulating means disposed adjacent to the member to be operated thereby, with parts broken away. Fig. 2 is a section on the line 2—2 in Fig. 1, with a part in full. Fig. 3 is a section on the line 3—3 in Fig. 2, with a part in full, and Figs. 4, 5 and 6 are sections on the lines 4—4, 5—5 and 6—6, respectively, in Fig. 2.

Referring to the drawings, 1 designates the bracket or carrying plate for the window member regulating means, such plate having a portion turned to form a broadened bearing 2. A cylindrical shell 3 of greater diameter than the bearing 2 has its inner end in the present instance outwardly flanged and seating against the plate 1 in concentric outwardly spaced relation to the bearing 2 and secured to the plate by rivets 4. The opposite end of the shell 3 is turned and formed in coaxial relation to the bearing 2 with a bearing 5, which is preferably broadened by an outward turning of the edge portion of the shell which forms such bearing. This bearing is preferably of smaller diameter than the bearing 2.

A shaft section 6, which may be termed the hand-control section, is journaled in the bearing 5, being projected at one end without said bearing to adapt it to receive an operating member, such for instance as a crank (not shown), and its inner end terminates within the shell and is preferably slightly enlarged to prevent its outward withdrawal through the bearing 5. This shaft is introduced through the bearing 2 in placing it in its bearing. The inner end of the shaft 6 is provided with an axial bore or socket 7 and the outer end of such socket opens into a cross recess 8 provided in the shaft end.

A shaft section 9, which may be termed the window-control section, is projected through the bearing 2 and journaled at its inner end in the socket 7 of the shaft section 6, while its outer end portion is provided with an enlarged journal portion 10 fitting in the bearing 2 for free turning movements therein. The portion 11 without the journal 10 of this shaft section is adapted to carry the arm or member (not shown) which is customarily employed to impart raising and lowering movements to the associated window member when the shaft is turned. The locking means employed in connection with the regulating mechanism is of the expanding clutch type and employs the shell 3 as the stationary member, while the movable expanding member thereof is disposed within the shell in encircling relation to the shaft section 9.

The movable clutch member comprises two halves disposed at diametrically opposite sides of the shaft and each preferably comprising two pieces 12 and 13, secured together by a rivet 14 in a manner to permit relative rocking movements of the pieces. The clutch pieces 12 are of segmental form adapted to fit the shell 3 to have peripheral clutch engagement with the inner peripheral wall thereof, and these pieces are yieldingly separated by coiled expansion springs 15 mounted in registering sockets provided in the inner adjacent edges of the pieces, two springs being provided, one at each of opposite sides of the shaft 9. The clutch pieces 13 at their inner or adjacent edges straddle a flattened or cam portion 16 of the shaft section 9 and coact therewith in such manner that a turning of the shaft 9 and its cam portion 16 in either direction will exert an outward expanding pressure

against the pieces 13 and communicate expanding or clutch engaging movement through them to the clutch pieces 12 by which they are carried.

5 Lugs 17 project laterally from the inner edge of each clutch piece 13 at opposite sides of the cam 16 and enter the end recess 8 of the shaft section 6. These lugs are intended to coact with the walls of said recess in such manner that a turning of the shaft section 6 in either direction will communicate a corresponding turning movement to the clutch pieces and through them to the shaft section 9, and at the same time 10 will tend to retract the clutch pieces 12 from clutch engagement with the shell 3. The purpose of making the elements of the movable clutch member in the two pieces, 12 and 13, instead of one, is to facilitate manufacture and to enable the pieces 13 to have a slight pivotal movement relative to the pieces 12 when power is applied through the shaft section 6, as this pivotal action is in some respects advantageous to the operation 15 of the device, although not essential. A filler-piece or washer member 18 is disposed between the members 12 and plate 1, intermediate the shell 3 and inturned shaft bearing portion of said plate.

20 From the above description it is apparent that if power is applied initially through the shaft section 6 to operate the control means to effect a raising or lowering of the associated window, such shaft section will act on the lugs 17 to effect a withdrawal of the clutch members 12 from frictional locking engagement with the shell 3 and will act through the pieces or portions 25 of such clutch members to impart rotation to the shaft section 9. On the other hand, if power is applied initially through the shaft section 9, as by an attempt to lower the associated window by application of pressure thereon, the turning action imparted to the shaft section 9 will cause its cam 16 to act on the clutch members to effect an expansion thereof to have locking or binding coaction with the shell 3.

It is evident that while I have particularly referred to the control means as being used in connection with a window member to effect a raising or lowering thereof, it may be used in other connections for which it may be adapted.

50 I wish it understood that my invention is not limited to any specific construction, arrangement or form of the parts, as it is capable of embodiment in numerous forms without departing from the spirit of the 55 claims.

Having thus described my invention, what I claim as new and desire to secure by Letters Patent, is:

60 1. In a mechanism of the class described, 65 a stationary clutch member, movable clutch

members disposed within and expandable for opposed locking engagement with the stationary member, two axially aligned relatively rotatable shaft sections, one when initially rotated coacting with the movable 70 clutch members to expand the same and the other when initially rotated acting on said members to retract the same and to drive the other shaft section.

2. In a mechanism of the class described, 75 a stationary clutch member, movable clutch members disposed within the stationary member and capable of expanding movements to have locking coaction with the stationary member, two axially aligned relatively rotatable shaft sections, one having cam coaction with the movable clutch members to adapt it when initially rotated to expand said clutch members, and the other having interengaging coaction with the 80 movable clutch members to adapt such shaft section when initially rotated to retract the movable clutch members and to act through said clutch members to impart rotation to the other shaft section. 90

3. In a mechanism of the class described, stationary means forming a cylindrical clutch shell and bearings at opposite end portions of the shell, two axially aligned relatively rotatable shaft sections projecting 95 within the shell and journaled in said bearings, one shaft section having a cam portion within the shell and the other shaft section having an end recess within the shell, opposed clutch members disposed within the shell and having coaction with the cam portion of one shaft section to adapt an initial turning of such shaft section to effect an expansion of the clutch members to have frictional locking coaction with the 100 shell, said clutch members also having portions projecting into the end recess of the other shaft section to adapt an initial turning of such shaft section to retract the clutch members from locking engagement with the 105 shell and to communicate turning movements to the other shaft section through the clutch members. 110

4. In a mechanism of the class described, stationary means forming a cylindrical clutch shell and axially aligned bearings at opposite end portions of the shell, segmental clutch members mounted in opposed relation within the shell and having laterally projecting lugs, two relatively rotatable shaft sections journaled in said bearings, one shaft section projecting between the clutch members and having a cam portion coacting with said members to effect an expansion thereof when power is applied initially through 115 such shaft section, and the other shaft section having a recessed portion receiving the lugs of the clutch members and operable to act on the lugs to effect a contraction of the clutch members and a turning of the shaft 120 125 130

section having the cam portion when power is initially applied through the other shaft section.

5. In a mechanism of the class described, 6 stationary means forming a cylindrical clutch shell and bearings at opposite ends of the shell, two axially aligned relatively rotatable shaft sections journaled in said bearings, one shaft section having a cam portion 10 within the shell and the other shaft section having an end portion terminating within the shell, opposed expanding clutch members mounted within the shell and each including a pivoted piece which coacts with

the cam portion of one shaft section and has 15 laterally projecting lugs interengaging with the adjacent end of the other shaft section, whereby power initially applied to one shaft section will actuate the cam thereof to expand the clutch members into locking engagement with the shell and power initially applied to the other shaft section will retract the clutch members from locking engagement with the shell and apply rotation to the other shaft section. 20 25

In testimony whereof, I have hereunto signed my name to this specification.

FIELDEN B. ASHENFELTER.
